Primary Examiner — Marissa J Cash

(57) **CLAIM**

The ornamental design for a cover for drone arms, as shown and described.

DESCRIPTION

FIG. 1 is a front right perspective view of a cover for drone arms in accordance with the present invention shown in a state of use with an unclaimed drone arm;

FIG. 2 is a rear right perspective view of a cover for drone arms in accordance with the present invention shown in a state of use with an unclaimed drone arm thereof;

FIG. 3 is a top plain view of a cover for drone arms shown removed when not in use and from drone arm environment for clarity of disclosure;

FIG. 4 is a rear right perspective of a cover for drone arms view shown removed when not in use and from drone arm environment for clarity of disclosure thereof;

FIG. 5 is a sectional view taken along line 5-5 in FIG. 2 of a cover for drone arms shown in a state of use with an unclaimed drone arm thereof; and,

FIG. 6 is a sectional view taken along line 6-6 in FIG. 4 of a cover for drone arms shown removed when not in use and from environment for clarity of disclosure thereof.

The broken lines in figures show environmental subject matter only and form no part of the claimed design.
